[57] CLAIM

The ornamental design for a slide type handle, as shown and
described.

DESCRIPTION

FIG. 1 is a perspective view of a slide type handle, showing
our new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof, the bottom plan view being
identical.
